FIG. 4.

UNITED STATES PATENT OFFICE

2,202,935

CARDIAC RECORDING APPARATUS

Harry Weiss, New York, N. Y.

Application June 18, 1938, Serial No. 214,466

5 Claims. (Cl. 128—2.05)

This invention relates to an automatic and graphic blood pressure recording device intended for use primarily in clinical and experimental cardiac work, or in any situation where a constant and automatic blood pressure record for a predetermined time is of value.

One of the objects of the invention is to provide an automatic and graphic blood pressure recording device which shall be useful in various environments, during sleep, at rest, or during various stages of activities; which shall be capable of automatic blood pressure recording for any desired period of time, or at predetermined intervals of time; which will permit the automatic and graphic determination of blood pressure changes, with changes in psychic, mental or physical state of the person being tested.

A further object of the invention is to provide means whereby the application and release of pressure on the artery of a patient may be recorded in the form of a curve similar to a sine curve on a photographic record strip and simultaneously therewith and as a part of the same curve, the arterial sounds occurring and disappearing during the application and release of pressure will also be recorded. The advantages of such an arrangement will be at once apparent to those skilled in this art.

In the accompanying drawings wherein an illustrative embodiment of the invention is shown, Fig. 1 is a side elevation, with parts in section, of a practical structure capable of performing the function desirous of being achieved by the invention; Fig. 2 is a plan view of the same; Fig. 3 is an end view of the structure; Fig. 4 is a diagrammatic view indicating the pump and connections thereto; and Fig. 5 shows the curve produced on a photographic record strip by the device forming the subject matter of the invention.

The apparatus shown in the accompanying drawings includes a flat base or support 1 which may be made of metal or of other desired material. Attached to said base, near one end thereof, is an inverted U-shaped supporting bracket 2 having laterally extended feet 3 and 4, which are secured to the base 1 by means of the screws shown or by any other suitable fastening elements. In the top portion of the bracket 2 is provided a rectangular slot 5, the sides of the top of bracket 2 adjacent said slot being tapped for the reception of the two set-screws 6 and 7. Fitted into the slot 5 is a socket 8 having an upper rectangular end of the same width as the slot 5 into which it fits, but of shorter length than said slot, so that it can be moved back and forth, or to-

ward the right and left as viewed in Fig. 1, and set in any desired position by means of the set-screws 6 and 7. The socket 8 is formed with a rounded lower end and in its center is formed with a recess 9 into which the pivot pin 14 may fit and rotate.

Directly below the socket 8 between the vertical legs of the bracket 2 is a similar socket 10 secured to the base 1, said socket having a central recess 11 for the reception of the pivot pin 13 on an oscilloscope 12. Said oscilloscope 12, sometimes known as an oscilloscope, is located within the bracket 2 and has its upper end provided with the pivot pin 14 located in the recess 9 on socket 8, and its lower end formed with the pivot pin 25 located in recess 11 of socket 10. This arrangement is such that the oscilloscope may rotate freely from side to side in its mounting in the two sockets 8 and 10.

The oscilloscope shown consists of a sealed casing or chamber 15 in which is fixed in oil a crystal element 16 such as shown as a "Bimorph" element, to the upper end of which is attached a filament 18 extending to the top of casing 15. A mirror 17 is attached on said filament. There are two contact members 19a and 19b leading from the crystal element, to which wires 24 may be attached, so that a current may be induced to flow through the crystal element to cause it and the attached mirror 17 to twist or rotate. A beam of light reflected from the mirror 17 will be projected through a window 20 formed in the upper portion of the casing 15 and will move with the movement of the mirror and will be recorded on a recording camera. The source of light can be directed from any suitable device independent of the apparatus shown, or it may be fixed to the base plate, to the bracket 2, or to the oscilloscope, or to the upper pivot pin thereof, which might be extended through the top of the bracket 2. Its position will mainly depend upon the desired placement of the camera, which will be controlled by factors of convenience and compactness.

An oscilloscope of the character described is available in the open market, one example of which is that known as the "Brush piezo-electric oscilloscope unit," manufactured by the Brush Development Co. of New York city. Such an oscilloscope unit consists of a thin, narrow, twister crystal element 16 cemented in Bakelite at one end and having its other end free to vibrate torsionally and attached to a small plane mirror 17 about one-eighth inch square, the leads being brought out through the pins or posts 19a and 19b inserted in the Bakelite base. This element

16 is located in a housing 15 consisting of a length of tube having its upper end terminating in a square head. A window 20 in the head, sealed by a lens, affords access to the mirror 17. Light 5 from the mirror 17 is brought to a focus by the lens without any additional optical part. The lens or window 20 is tilted slightly downward so that any light reflected from its surface will not interfere with light reflected from the mirror.

10 The housing is filled with oil which serves as a damping agent and also protects the crystal from physical shocks due to rough handling. While a crystal oscilloscope is herein described, it will be apparent that any other known type of 15 oscilloscope including electrically motivated oscilloscopes can function in the same way.

15 The current serving to actuate the oscilloscope element and mirror to cause them to move within the casing 15 is obtained through the leads 24 connecting to the binding posts 19a and 19b. Leads 24 connect to microphone 21a or other source of current which is adapted to be applied to the arm of a patient in the antibrachial space below the blood pressure cuff. The current from 20 this microphone induced by the sound produced at the antibrachial space of the arm, then passes through appropriate apparatus including a variable induction coil 22 and variable resistance 23 through the leads 24 to binding posts 19a and 25 19b. As the sound is produced at the microphone, the mirror within the oscilloscope will twist and the beam of light therefrom will be reflected into a camera which will thus record the movement of the mirror.

30 35 Rigidly attached to the lower pivot pin 13 or to the lower end of the oscilloscope casing 15 or at any other suitable location therein, is a segmental gear 26. This gear meshes with a second gear or pinion 27 secured to a pivotal shaft 28 at point 29. Said shaft 28 is part of an aneroid 30. An aneroid suitable for the purpose is that known as the "Tycos" although other makes may be used. The body of the aneroid 30 is rigidly secured to a supporting saddle 31 fastened to the 40 base plate 1 by means of appropriate screws, rivets or welding. To stabilize the mounting of the aneroid, the pivotal shaft 28 thereof is mounted in a socket 32 secured on the upper face of the base 1. The air entrance and outlet of the 45 aneroid comprises the nipple 33 to which is attached a tube 34 extending to a T-shaped connection 35 leading to an air pump 36 diagrammatically illustrated in Fig. 4. The piston 37 of this pump is pivotally attached to connecting rod 50 55 38 which in turn extends to the crank shaft or to the eccentric of a motor not shown, but of conventional structure, which acts to reciprocate the piston 37 in cylinder 36 in the usual way. The other leg of the T-shaped connection 35 attaches 60 to a tube 39 which extends to a three-way valve 40. By means of this three-way valve, two other connections are made, one through a tube 41 to a hand bulb not shown, but of the type commonly used in the ordinary blood pressure apparatus, 65 and to which is attached a by-pass to the outside air which can be closed; the other to a tube 42 which extends to an arm cuff not shown but of the conventional kind known as a blood pressure cuff, adapted to be attached to the arm to encircle it just above the point of application or attachment of a microphone at the antibrachial space.

70 The hand bulb connected to tube 41 can be used during manual inflation and deflation of the apparatus and can be used for purposes of

adjustment. During the automatic operation of the apparatus, the hand bulb is closed off at the three-way valve 40 and the arm cuff is open to the pump 36.

75 In operation the apparatus functions as follows: The piston 37 is slowly reciprocated in cylinder 36 by slow operation of the motor to which the piston is connected. The movement of piston 36 in cylinder 37 causes the movement of air into and out of the aneroid 30 through tube 34 and 10 in and out of the arm cuff connected to the tube 42. With this rise and fall of air pressure in the system there is a corresponding oscillating movement of the shaft 28 of the aneroid clockwise and counter-clockwise through a predetermined 15 arc. As this movement occurs, the gear 27 is moved and through its mesh with the segmental gear 26, the latter gear is caused to oscillate, causing the oscilloscope to which it is attached, to rotate counter-clockwise and then clockwise 20 with the rise and fall of the air pressure.

If a beam of light is reflected from the mirror 17 onto the moving sensitized film or paper of a camera, a line is obtained thereon resembling a sine curve, which is smooth and unbroken and 25 represents the base line upon which the subsequent blood-pressure readings are to be represented. This base line is calibrated to extend between any desired blood pressure levels by means of the amount of displacement allowed the 30 piston 37 within the cylinder 36. This can be regulated in numerous ways, such as by changing the position of the pump cylinder on its base or by adjusting the degree of eccentricity of the piston on its attachment to the driving motor. This 35 will adjust the amplitude of the curve and the height to which it is desired to carry the curve peak in order to cover the expected blood-pressure range. The lower point of this basic curve is adjusted through the hand bulb. The resultant 40 smooth basic curve is shown at a in Fig. 5.

If it is desired to work up to a higher level, as just explained, and the displacement of the piston is altered to secure that result, the resultant curve will resemble that shown at b in 45 Fig. 5.

As the apparatus is being alternately inflated and deflated by the pump and the basic line is being produced as just described, the pressure in the arm cuff, received through tube 42, rises and 50 falls in corresponding manner. As the pressure rises from zero to the diastolic pressure, no sound is produced in the antibrachial space, or only a very slight sound up to the point of diastole where the sound changes due to the fact that the artery 55 is now being compressed. This sound is detected by the microphone 21 secured over the artery in this space. As the pressure continues to rise these sounds persist with each heart beat until the pressure rises to the point of systole when 60 the sounds disappear due to the fact that the artery is now completely occluded. As the pressure falls, the same thing occurs except that the sequence of events is now reversed.

The sounds produced in the antibrachial 65 space of the arm are picked up by the microphone 21 and result in the electrical impulses which are transmitted to the crystal 16 of the oscilloscope causing said crystal to distort or twist and simultaneously to twist the mirror 17 70 through the suspension filament 18. This distortion or twisting movement of the mirror 17 causes a deviation from the form of base line produced, and as previously described and shown at a and b, resulting in the production of irregu- 75

larities in the line which represent at their beginning and ending the points of systole and diastole. Such a line with the distortions present is shown at c in Fig. 5.

5. Automatic control of the apparatus is readily attained by means of a simple time switch which will simultaneously switch on the pump motor, the camera motor, the source of light, the microphone and any other electrically operated elements of the apparatus, and after a given time, switch these elements off. Various other changes and additions may be readily made without departing from the spirit of the invention as expressed in the annexed claims.

15. What I claim is:

1. In an apparatus of the character described, an oscilloscope mounted for oscillatory movement and provided with an oscillating mirror, means for mechanically oscillating the oscilloscope, a pump having its output connected to a blood-pressure cuff and to the oscilloscope-oscillating means whereby the application and release of pressure in the cuff by operation of the pump will cause the oscilloscope to be oscillated, means for recording on a line such movements of the oscilloscope and means for recording vibratory movements of the mirror on the same single recording line while the oscilloscope is being moved under action of the 30 pump.

2. In an apparatus of the character described, an oscilloscope including a light-transferring element, means for oscillating the oscilloscope through a predetermined path, said means including an air pressure device for automatically supplying to and releasing pressure on the oscillating means, means for recording on a record line the oscillatory movements of the oscilloscope, and means for recording on the same record line arterial sounds by movements of the light-transferring element while the oscilloscope is being moved.

3. In an apparatus of the character described, a supporting base, a crystal oscilloscope mounted for oscillatory movement thereon, said oscilloscope including a filament-supported mirror for directing a light beam, gearing connected

to said oscilloscope for bodily oscillating the same, an aneroid having an oscillating shaft for driving said gearing, a pump for alternately applying and releasing air pressure on the aneroid, a blood pressure cuff, a connection between the pump and cuff, a microphone and connections between the same and the crystal of the oscilloscope whereby sounds picked up by the microphone will be electrically transmitted to the crystal to cause the mirror to be oscillated while the oscilloscope is being oscillated by pump impulses.

4. In an apparatus of the character described, a supporting base, a crystal oscilloscope mounted for oscillatory movement thereon, said oscilloscope including a filament-supported mirror for directing a light beam, gearing connected to said oscilloscope for bodily oscillating the same through a predetermined path, an aneroid having an oscillating shaft for driving said gearing, a pump for alternately applying and releasing air pressure on the aneroid, a blood pressure cuff, a connection between the pump and cuff by which air pressure will be supplied and relieved by the pump to the cuff simultaneously with the application and release of pressure to the aneroid, a microphone and connections between the same and the crystal of the oscilloscope whereby sounds picked up by the microphone will be electrically transmitted to the crystal to cause the mirror to be oscillated while the oscilloscope is being oscillated by pump impulses.

5. In an apparatus of the character described, a crystal oscilloscope including a mirror, a pivotal mounting for said oscilloscope whereby the same may have oscillatory movements, means for imparting a uniform oscillatory movement to the oscilloscope, and means connected to a patient's arm and to the oscilloscope for causing sounds occurring between the points of systole and diastole to be imparted as vibrations to the mirror of the oscilloscope during the uniform oscillatory movement of the oscilloscope, and means for recording the oscillatory movements of the oscilloscope and the vibratory movements of the mirror on a single line.

HARRY WEISS.
